WASHING MACHINE

Carl E. Lang, Berkeley, Calif.

Application March 23, 1938, Serial No. 197,638

14 Claims.

(Cl. 68—21)

The present invention relates to washing machines, and more particularly to a washing machine of the type having an oscillating and elevating agitator that operates when oscillating to wash the clothes, and which when elevated cooperates with an overhanging pressure resisting member to extract water from the clothes preliminary to their removal from the machine.

An object of the invention is to provide a new, novel and improved form washing machine having the above features, which is practical, effective and inexpensive to manufacture.

Another object of the invention is to provide an improvement in washing machines of the type employing an oscillating agitator, wherein the agitator is adapted to be raised and cooperate with a fixed pressure resisting member to extract water from the clothes after washing.

Another object of the invention is to provide a new and novel form of mounting for the oscillating agitator element of a washing machine, which will permit an elevation of the agitator element within the tub for the purpose of squeezing the water out of clothes carried thereby, in a simple and convenient manner.

Another object of the invention is to provide a new and novel agitator element for washing machines of the type having an oscillating and vertically movable agitator means, in which the agitator means is provided with radially disposed agitator vanes that move into an operative position when the agitator element is in its clothes washing position, and move out of engagement with the clothes when the agitator element is elevated, as when squeezing water from the clothes.

Another object of the invention is to provide a new and practical arrangement wherein an expandible fluid containing flexible member cooperates with an elevated clothes carrying member in a novel manner to squeeze water from the clothes.

A further object of the invention is to provide a new and novel arrangement in a washing machine of the type having an oscillating and elevating clothes carrying agitator means, wherein the agitator means may be selectively coupled to a driving motor to impart either an oscillating movement or an elevating movement thereto in a simple and convenient manner.

Other objects and advantages of the invention will be in part evident to those skilled in the art and in part pointed out hereinafter in connection with the accompanying drawings, wherein there is

shown by way of illustration and not of limitation, preferred embodiments thereof.

In the drawings, wherein like numerals refer to like parts throughout the several views:

Figure 1 is a vertical sectional view of a washing machine constructed in accordance with the invention, with the parts in their clothes washing position.

Figure 2 is a view similar to Figure 1, showing the parts in the positions assumed when the machine is operating to squeeze water from the clothes.

Figure 3 is a plan view of the washing machine, with certain parts in section, to disclose details of construction.

Figure 4 is a horizontal sectional view, taken along line IV—IV of Figure 2, looking in direction of arrows.

Figure 5 is a fragmentary enlarged perspective view, showing details of a portion of the driving mechanism, and

Figure 6 is a fragmentary perspective view, showing further details of construction of a machine constructed in accordance with this invention.

As illustrated in Figures 1 and 2 of the drawings, the apparatus chosen to illustrate the present invention includes a clothes receptacle or tub 10 having a cover 11 which is adapted to be placed thereover during the clothes washing operation.

The tub 10 is supported upon a cylindrical foundation or support 12 and mounted upon brackets 13 within the foundation 12 there is a gear box 14 having a suitable motor driven mechanism 15 by means of which the various elements of the washing machine are operated, as will be described in detail hereinafter.

At this point it will be sufficient to state that the apparatus contemplates both a washing and squeezing of the wash water from the clothes. The tub 10 has a centrally disposed hollow upwardly extending stationary pedestal 16, and at the upper end of this pedestal 16 there is a bushing 17 through which a vertically movable tubular support 18 is adapted to slide and also oscillate.

Extending upwardly into the vertically movable tubular support 18 there is a screw threaded shaft 19 with which the lower end of the tubular support 18 has a threaded connection as at 20. At the upper end of the tubular supporting member 18 there is a hexagonal extension 21 which provides a splined connection or mounting for a saddle-like member 22 that extends downwardly over the outside of the hollow stationary pedestal 16 to a point adjacent the bottom of the tub 10. At its lower end the saddle-

55

like member 22 supports a clothes carrying agitator 23 upon which there is pivotally mounted a plurality of agitator vanes 24. The agitator vanes 24 are preferably arranged radially upon the clothes carrying member 23 and are located in slots which permit a downward pivotal movement thereof through the bottom of the clothes carrying member 23 when this member is elevated, as will hereinafter appear. The agitator vanes 24 are pivoted between suitably spaced ears 25 which extend outwardly from the bottom of the clothes carrying member 23. Arranged in the bottom of the tub 10, at a point where it will be engaged by the lower edges of the agitator vanes 24, there is a plate-like member 26 that serves to hold the agitator vanes in an operative position, as illustrated in Figure 1 of the drawings, when the washing machine is operating to wash clothes. When the parts are in this position the lower end of the tubular supporting member 18 will be extended out of the hollow stationary pedestal 16, so that its threaded end 20 can be engaged by a slideable clutch collar 27 to connect the clothes carrying member 23 and the agitator vanes 24 though the saddle-like member 22 to the motor driven mechanism 15, as will also hereinafter appear. At this point it may be pointed out that when the apparatus is connected, as has been above described, and the motor driven mechanism 15 is operated by a motor 28, the clothes carrying member 23 with the agitator vanes 24 will be oscillated within the tub 10, so that the clothes will be subjected to a washing action, as is well understood in the art.

Reference is now made to Figure 2 of the drawings, for a description of another aspect of the present invention. In this figure of the drawings it will be noted that the clutch collar 27 has been moved downwardly so that pins 29 carried thereby are projected into a worm gear 30 of the motor driven mechanism 15. When the clutch collar 27 is thus moved downwardly into the position illustrated, the oscillating connection between the driving mechanism 15, the clothes carrying member 23 and its agitator vanes 24 will be rendered ineffective, and at the same time the pins 29 upon the clutch collar 27 will connect the screw threaded shaft 19 directly to the worm gear 30. As a result of this connection, when the worm gear 30 is driven by the motor 28, the screw threaded shaft 19 will be rotated in a continuous direction and move the tubular supporting member 18, due to its threaded connection, either up or down within the hollow stationary pedestal 16. When the screw threaded shaft 19 is rotated in a forward direction, the tubular supporting member 18 will be caused to move upwardly within the hollow stationary pedestal 16 and carry the overhanging saddle-like member 22 also upwardly. This will raise the clothes carrying member 23 and any clothes carried thereby out of the washing water, designated by the numeral 31. As the clothes carrying member 23 is thus raised out of the washing water 31, the agitator vanes 24 carried thereby will be moved away from the plate-like member 26 at the bottom of the tub 10, and as a result these agitator vanes will move downwardly about their pivotal supports 25 and into the positions shown in this figure of the drawings. In order to prevent a displacement of the agitator vanes 24 from their respective slots in the bottom of the clothes carrying member 23, the supporting ears 25 are provided with an abutment 32 which serves to hold the agitator vanes 24 with their upper edges

substantially flush with the inside surface of the clothes carrying member 23.

From the above it will be seen that by connecting the screw threaded shaft 19 directly to the motor driven mechanism 15, it is possible to elevate the clothes, designated by the numeral 33, out of the washing water 31. In order to utilize this feature of the invention for the wringing or squeezing of water from the clothes 33, the tub 10 is provided with a swingable arm 34 that is mounted upon the upper end of a vertical shaft 35 which is journaled in bearings 36 and 37 upon the side of the tub 10. This permits the swingable arm 34 to be positioned over the tub 10 during the clothes squeezing operation of the machine. The extending end of the arm 34 has three smaller radially extending arms 38 to which there is secured a semiannular supporting member 39, to the underside of which there is secured a fluid containing expandable member 40. The member 40 may be of any suitable construction. In the drawings the member 40 is shown as made of a heavy rubber tube-like material which is closed at its ends. For the purpose of inflating the fluid containing expandable member 40 there is shown a connection 41 having a valve 42 and hose connection 43 which connects with the interior thereof. This collapsible member 40 is adapted to be inflated and expanded by the admission thereto of water or any other fluid under pressure. In order to secure the swingable arm 34 and the members 39 and 40 in a concentric operative position with respect to the clothes carrying member 23, and to prevent a vertical displacement thereof when pressure is exerted thereupon, the overhanging end of the swingable arm 34 is secured in place by means of an interlocking washer-like member 44 that engages an overhanging flange 45 upon the bushing 17 at the upper end of the hollow stationary pedestal 16.

Upon referring to Figure 3 of the drawings, it will be noted that the swingable arm 34 is cut out between two of the smaller supporting arms 38 so as to permit its overhanging end to move into a position concentric with the hollow stationary pedestal 16. It will also be noted that the semiannular supporting member 39 is also cut out, as at 46, so as to permit its movement into concentric relation with the tub 10 when the arm 34 is in its operative position, as shown. In this figure of the drawings it will also be noted that the expandable member 40 has its ends arranged so as to permit its movement with the swingable arm 34 into a position substantially concentric with the clothes carrying member 23. As shown in this figure of the drawings, the interlocking washer-like member 44 has two oppositely disposed inwardly projecting tongues 46 that extend under the flange 45 upon the bushing 17 at the upper end of the hollow stationary pedestal 16. The tongues 46 upon the interlocking washer-like member 44 are made sufficiently long to permit a disposition of the washer-like member 44 around the outside of the saddle-like support 22, and to accommodate these tongues 46 upon the washer-like member 44, the saddle-like member 22 is provided with oppositely disposed vertical slots 47 which permit relative vertical movement between the washer 44 and the saddle-like member 22, as when the clothes carrying member 23 is being elevated and lowered in the tub.

Reference is now made to Figure 4 of the drawings, for a description of the motor driven mechanism 15 which, as suggested above, operates to

drive the clothes washing and squeezing elements of the apparatus. As shown, the movements of the slidable clutch collar 27 are controlled by a forked yoke 48 secured upon the end 5 of a shaft 49 and from which there extends a suitable foot or hand operated lever 50. This lever 50 is shown as extending out through a wall of the foundation or support 12 upon which the tub 10 is mounted, where it can be operated by foot or hand as desired. The shaft 49 is also shown as having a short lever arm 51 which connects through a link 52 with a crank arm 53 carried by an eccentric shaft 54. Mounted upon the eccentric shaft 54 there is an oscillatable gear sector 55 that meshes with a smaller gear 56 which is shown as secured upon the screw threaded shaft 19 by means of a pin 57. The oscillatable gear sector 55 is also shown as having an outwardly extending arm 58 to which one end 20 of an offset link 59 is connected. The other end of the offset link 59 is connected to a crank pin 60 carried by an additional gear 61 which permanently meshes with gear teeth 62 formed upon the worm gear 30. At this point it will be noted that 25 the worm gear 30 is adapted to be driven by a worm 63 that is directly connected to the motor 28 by means of a shaft 64.

With the above arrangement it will be seen that when the hand or foot operated lever 50 is moved from one of its extreme positions to another, the forked yoke 28 will be moved to carry the slidable collar 27 either up or down. At the same time the lever arm 51 upon the shaft 49 will operate through the link 52 and the crank arm 53 to rotate the eccentric shaft 54 so as to move the gear sector 55 into and out of engagement with the gear 56 which is secured upon the screw threaded shaft 19. At this point it should be stated that the disposition of the forked yoke 48 with respect to the lever arm 51 carried by the shaft 49 is such that when the slidable collar 27 is in its uppermost position, as shown in Figure 1, the gear sector 55 will be in mesh with the gear 56, whereas when the slidable collar 27 is in its lowermost position, as illustrated in Figure 2 of the drawings, the gear sector 55 will be held out of meshing engagement with the smaller gear 56 upon the screw threaded shaft 19. This latter position of the parts will 50 permit a continuous rotation of the screw threaded shaft 19 in one direction. During this operation of the machine, the gear sector 55 will continue to oscillate as the gear 61 will continue to rotate, but during this period of operation the gear sector 55, as stated above, will be held out of engagement with the smaller gear 56 upon the screw threaded shaft 19. At the same time, when the slidable collar 27 is in its lowermost position, the pins 29 carried thereby will be projected 55 through the smaller gear 56 and into the worm gear 30, so as to provide a direct driving connection from the worm gear 30 to the screw threaded shaft 19 for elevating and lowering the clothes carrying member 23 in the tub.

Upon referring to Figure 5 of the drawings, it will be noted that the vertically movable supporting member 18, in addition to being threadedly connected at its lower end to the screw threaded shaft 19, also has a series of spline forming 70 grooves 65 into which spline forming tongues 66 carried by the slidable collar 27 are adapted to be moved to effect a driving connection between the slidable collar 27 and the vertically movable supporting member 18 when the motor 75

driven mechanism 15 is operating to oscillate the clothes carrying member 23.

Reference is now made to Figure 6 of the drawings, for a detailed description of the means provided at the upper end of the hollow vertical pedestal 16 for securing the swingable arm 34 against vertical displacement during the clothes squeezing operation of the machine. In this figure of the drawings a portion of the saddle-like member 22 has been broken away to uncover the flanged end of the bushing 17 which is threaded into the upper end of the hollow vertical pedestal 16. As is shown by this illustration, the flange 45 upon the bushing 17 has oppositely disposed slots 67 through which the tongues 46 15 upon the washer-like member 44 may be passed before being rotated into interlocking relation with the flange 45 of the bushing 17. It will be understood that during the downward movement of the tongues 66 upon the member 44 through 20 the slots 67 in the flange 45, the vertical slots 47 in the saddle-like member 22 will be aligned with the slots 67. When the tongues 46 upon the washer-like member 44 have been passed through the slots 67, they can be rotated into interlocking 25 relation with the flange 45 upon the bushing 17 by a slight turning of the saddle-like member 22. After the washer-like member 44 has been thus positioned upon the end of the swingable arm 34, the slots 47 in the saddle-like member 22 will 30 permit a free upward and downward movement of this member without disturbing the interlocking connection between the flange 45 and the tongues 46 upon the washer-like member 44. If desired, the washer-like member 44 may be provided with a radially extending handle or lever for turning it into interlocking relation with the flange 45 upon the bushing 17. Means such as a set screw may also be provided for securing these parts in their interlocking positions if found necessary.

The operation of the apparatus disclosed above, may be described as follows: When the machine is to be used for the washing operation, the parts will be in the positions illustrated in Figure 1 45 of the drawings. Under these conditions the clothes carrying member 23 will be in its lowermost position at the bottom of the tub 10 with the agitator vanes 24 elevated by the plate 26 so as to engage the clothes and cause them to 50 be oscillated in the washing water as the clothes carrying member 23 is oscillated. It will be assumed that the motor 28 has been started by any suitable switch and that the slidable clutch collar 27 is in its uppermost position, where it is 55 in splined engagement with the lower end of the tubular support 18. Under these conditions, as the motor 28 continues to operate it will drive the worm gear 30, and through the gear teeth 62 formed thereupon, the gear 61 will be also rotated 60 continuously in one direction. This rotation of the gear 61 will cause the crank pin 60 carried thereby, to impart a reciprocating movement to the offset link 59, as shown in Figure 4 of the drawings, and this movement of the link 59 will 65 in turn cause the oscillatable gear sector 55 to oscillate and thus impart an oscillating movement to the smaller gear 56. This oscillating movement of the smaller gear 56 will then be transmitted through the pins 29 carried by the 70 clutch collar 27 to the tubular support 18, which in turn will oscillate the clothes carrying member 23 with the clothes through the medium of the saddle-like supporting member 22. During this operation of the machine the swingable arm 34 75

will be swung out into a position clear of the tub so that the cover 11 may be placed thereover.

When the apparatus is operated to squeeze water from the clothes, the parts at the end of the squeezing operation will be substantially in the positions illustrated in Figure 2 of the drawings. This operation is accomplished by throwing the foot or hand lever 50 down so as to move the slideable clutch collar 27 out of its splined engagement with the lower end of the tubular support 18 and project the pins 29 carried thereby into the worm gear 30. This downward movement of the foot or hand lever 50, as has been described above in connection with Figure 4 of the drawings, will also rotate the eccentric shaft 54 so as to move the gear sector 55 out of engagement with the smaller gear 56 secured to the lower end of the screw threaded shaft 19. If the motor 28 is now connected to the power circuit for forward rotation, the worm 63 will drive the worm gear 30, and thus, through the medium of the pins 29, the screw threaded shaft 19 will be rotated in a forward direction. This will cause the tubular support 18 with its threaded connection upon the shaft 19 to move upwardly and carry the saddle-like support 22 with the clothes carrying member 23 and the clothes upwardly. During the initial upward movement of the clothes carrying member 23 the agitator vanes 24 carried thereby, will swing downwardly until they engage the abutments 32 carried by the supporting ears 25.

It will be understood that prior to the above operation of the apparatus, the swingable arm will be swung over the tub so as to bring the semi-annular support 39 and the expandable member 40 into a position concentric with the clothes carrying member 23, where it will be secured by the washer-like member 44, as has been previously pointed out in connection with Figure 6 of the drawings. The expandable member 40 may be partially filled with a fluid, or it may be completely inflated. If this member is completely inflated, the continued upward movement of the clothes carrying member 23 will bring the clothes into engagement with the member 40, and as pressure is applied by a further rotation of the screw threaded shaft 19, the water will be squeezed from the clothes.

In accordance with another aspect of the invention, it is contemplated that the expandable member 40 may be empty or only partially filled when the clothes are moved into engagement therewith, and that subsequently water or other fluid under pressure may be admitted thereto, to produce the pressure for squeezing the water out of the clothes. In this latter event, the clothes carrying member 23 will be elevated to a suitable height, after which the motor 28 will be stopped. Then the pressure will be exerted upon the clothes by the admission of a fluid to the expandable member 40. In either event, after the clothes have been squeezed, the fluid will be allowed to flow from within the expandable member 40 and thus relieve the pressure upon the clothes to permit their ready removal from the clothes carrying member 23 without necessitating a lowering of this member, which might bring the clothes into contact with the water in the tub 10.

In connection with the fluid used in the expandable member 40, it may be said that this may be water at city pressure, or the water may be circulated through a suitable pump to produce the pressure desired. It is contemplated that where air under pressure is available, such

a fluid may be used. It is also contemplated that the driving connection between the motor 28 and the worm 63 may be provided with a torque responsive circuit controlling switch, as is disclosed in my copending application, Serial No. 5 51,413, filed November 25, 1935, for Washing machine, issued February 14, 1939, as Patent No. 2,147,303.

While I have, for the sake of clearness and in order to disclose my invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is—

1. In a clothes washing machine of the character described, the combination of a stationary tub adapted to contain a washing fluid, a hollow stationary pedestal disposed centrally within said tub and extending above the top thereof, a screw threaded shaft extending upwardly into said hollow stationary pedestal, motor driven means for driving said screw threaded shaft in a forward and reverse direction, a tubular agitator supporting element movable vertically within said hollow stationary pedestal over said screw threaded shaft and having a threaded connection with said screw threaded shaft, a saddle-like supporting member engaging the upper end of said tubular agitator supporting element and extending downwardly over the outside of said hollow stationary pedestal and into said tub, a dished agitator element carried by said saddle-like supporting member, a plurality of agitator vanes pivotally mounted upon said agitator element adapted to move downwardly into an inoperative position when said agitator element is elevated by a turning of said screw threaded shaft, and means at the bottom of said tub arranged so as to engage said agitator vanes and move them upwardly into an operative position when said agitator element is lowered into the tub.

2. In a clothes washing machine of the character described, the combination of a stationary tub adapted to contain a washing fluid, a hollow stationary pedestal disposed centrally within said tub and extending above the top thereof, a screw threaded shaft extending upwardly into said hollow stationary pedestal, motor driven means for driving said screw threaded shaft in a forward and reverse direction, clutch means for connecting said screw threaded shaft to said motor driven means, a hollow agitator supporting element movable vertically within said hollow pedestal over said screw threaded shaft and having a threaded connection at its lower end with said screw threaded shaft, a saddle-like supporting member secured to the upper end of said agitator supporting element and extending downwardly over the outside of said hollow stationary pedestal and into said tub, an agitator element at the lower end of said saddle-like supporting member, a plurality of agitator vanes pivotally mounted upon said agitator element arranged to move downwardly into an inoperative position when said agitator element is elevated by a turning of said screw threaded shaft in one direction, and means at the bottom of said tub arranged

so as to engage said agitator vanes and move them upwardly into an operative position when said agitator element is lowered into the tub by a turning of said threaded shaft in a reverse direction.

5 3. In a clothes washing machine of the character described, the combination of a stationary tub adapted to contain a washing fluid, a hollow stationary pedestal disposed centrally within said tub and extending above the top thereof, a screw threaded shaft extending upwardly into said hollow stationary pedestal, a tubular agitator supporting member movable vertically within said hollow pedestal support and having a splined 10 projecting end and a threaded connection with said screw threaded shaft, a saddle-like supporting member movable with and engaging the upper end of said agitator supporting means and extending downwardly over the outside of said pedestal-like support and into said tub, an agitator element suspended in said tub and carried by said saddle-like supporting member, a motor driven means for rotating said screw threaded shaft in a forward and a reverse direction to 15 raise and lower said saddle-like support and said agitator with respect to the tub, said motor driven means being also adapted to impart an oscillating movement to said saddle-like supporting member and the agitator carried thereby, and a 20 selectively operating clutch means for connecting said motor driven means to said screw threaded shaft or to the splined end of said saddle-like supporting member when the latter member is in its lowermost position to respectively raise and 25 lower said agitator or oscillate same with respect to said tub.

4. In a washing machine of the character described, the combination of a stationary tub having a centrally disposed tubular pedestal arranged therein, a screw threaded shaft extending upwardly into said pedestal, an agitator supporting member extending downwardly into said tubular pedestal having a threaded connection with said screw threaded shaft, said agitator supporting member also having a splined extension 40 at the lower end thereof adapted to project out of said tubular pedestal when in its lowermost position, an agitator disposed within the tub and suspended from said supporting member, a power driven mechanism for rotating said screw 45 threaded shaft in either direction or oscillating said agitator supporting member within said tubular pedestal, and a selectable driving connection associated with said power driven mechanism adapted to provide a connection thereof with said screw threaded shaft to elevate said agitator supporting member or with the splined end of said agitator supporting member when in its lowermost position to produce an oscillatory 50 movement thereof.

5. In a washing machine of the character described, the combination of a stationary tub having a centrally disposed tubular pedestal arranged centrally therein, a screw threaded shaft 55 extending upwardly into said pedestal, an agitator supporting member extending downwardly into said tubular pedestal having a threaded connection with said screw threaded shaft, said agitator supporting member also having a splined extension at the lower end thereof adapted to project out of said tubular pedestal when in its lowermost position, an agitator secured upon said supporting member and disposed in the tub, a power driven mechanism for rotating said screw 60 threaded shaft in either direction or oscillating 65

said agitator supporting member within said tubular pedestal, and a selectable driving connection associated with said power driven mechanism adapted to provide a connection thereof with said screw threaded shaft to elevate said agitator and supporting member or with the splined extension of said supporting member to produce an oscillatory movement of said agitator within the tub.

6. In a washing machine of the character described, the combination of a clothes containing tub, a clothes carrying and agitating member disposed within said tub, means for elevating said clothes carrying and agitating member to press water out of the clothes carried thereby, a pressure resisting member adapted to be secured in a fixed position above said clothes carrying member, a yieldable fluid containing member secured upon the under side of said pressure resisting member against which the clothes when lifted 20 out of the tub by said elevating means will be pressed to squeeze the water therefrom, and means for discharging the fluid from said fluid containing member to thereby relieve the pressure upon the clothes and permit removal of same 25 without a lowering of the clothes carrying member.

7. In a washing machine of the character described, the combination of a stationary tub, a clothes carrying and agitating member disposed 30 within said tub, means secured at the bottom of said tub for elevating said clothes carrying and agitating member to press the water out of the clothes carried thereby, a swingable support adapted to be positioned centrally above said 35 clothes carrying member, a yielding fluid containing member secured upon the underside of said support against which the clothes when lifted out of the tub by said elevating means will be pressed to remove the water therefrom, and a pressure resisting connection between said swingable support and the means at the bottom of the tub for elevating said clothes carrying member, said connection extending centrally through said 40 yielding fluid containing member and said clothes carrying member.

8. In a washing machine of the character described, the combination of a stationary tub having a centrally disposed tubular pedestal arranged therein, a screw threaded shaft extending 50 upwardly into said pedestal, a supporting member extending downwardly into said tubular pedestal having a threaded connection with said screw threaded shaft, a clothes carrying member suspended from said supporting member and disposed within the stationary tub about said tubular pedestal, a power driven mechanism for rotating said screw threaded shaft in either direction to raise and lower said clothes carrying member within said tub, a swingable pressure 55 resisting member of semi-circular configuration adapted to be positioned substantially concentric with the upper end of said tubular pedestal, and means associated with said pressure resisting member interlocking with the upper end of said tubular pedestal to prevent vertical displacement of said pressure resisting member when said screw threaded shaft is rotated to raise said clothes carrying member to squeeze water out of 60 the clothes carried thereby.

9. In a washing machine of the character described, the combination of a stationary tub having a centrally disposed tubular pedestal arranged therein, a screw threaded shaft extend- 70

ing upwardly into said pedestal, a supporting member extending downwardly into said tubular pedestal having a threaded connection with said screw threaded shaft, a clothes carrying member suspended from said supporting member and disposed within the stationary tub, a power driven mechanism for rotating said screw threaded shaft in either direction to raise and lower said clothes carrying member within said tub, a swingable pressure resisting member of semicircular configuration adapted to be positioned substantially concentric with the upper end of said tubular pedestal, means associated with said pressure resisting member interlocking with the upper end 15 of said tubular pedestal to prevent vertical displacement of said pressure resisting member when said screw threaded shaft is rotated to raise said clothes carrying member to squeeze water out of the clothes carried thereby, and a 20 fluid containing collapsible means carried by said swingable pressure resisting member against which the clothes are pressed and adapted when the fluid is discharged therefrom to permit a removal of the clothes without a lowering of said 25 clothes carrying member.

10. In a washing machine of the character described, the combination of a stationary tub having a tubular pedestal arranged centrally therein, a screw threaded shaft extending upwardly into 30 said pedestal, a supporting member extending downwardly into said tubular pedestal having a threaded connection with said screw threaded shaft, said supporting member also having a splined extension at the lower end thereof 35 adapted to project out of said tubular pedestal when in its lowermost position, a clothes carrying member having radial slots in which agitator vanes are positioned suspended from said supporting member and disposed within the station- 40 ary tub, a power driven mechanism for rotating said screw threaded shaft in either direction to raise and lower said clothes carrying member within said tub, a clutch means for selectively engaging the splined end of said supporting mem- 45 ber to connect same to an oscillating mechanism when the clothes carrying member is lowered into the tub, a plurality of radially disposed agitating vanes pivotally mounted upon said clothes carrying member and, movable vertically through the 50 slots therein as said clothes carrying member is raised and lowered, stop means for limiting the downward movement of said vanes to an inoperative position when said clothes carrying 55 member is elevated, and means for raising said agitator vanes into an operative position when said clothes carrying member is lowered into the tub.

11. In a clothes washing machine of the character described, the combination of a stationary tub, a clothes carrying member mounted within said tub, means for elevating said clothes carrying member to remove the clothes from the water within said tub after washing, a support swing- 60 ably mounted upon the side of said tub, an expandable fluid containing member mounted on said swingable support adapted to be positioned over the clothes upon said clothes carrying member, and means for admitting a fluid under pres- 65 sure to the interior of said expandable member, whereby said expandable member will expand and exert a pressure against the clothes upon said clothes carrying member to squeeze water therefrom when the clothes are raised out of the 70 water in the tub.

12. In a clothes washing machine of the character described, the combination of a stationary tub, a clothes agitating member mounted within said tub, means for elevating said clothes agitating member to raise the clothes from the water within said tub after washing, a swingable support mounted upon the side of said tub adapted to be positioned centrally thereover, an expandable fluid containing member of substantially annular configuration mounted upon said swingable 10 bracket adapted to be positioned centrally above said clothes agitating member, and means for admitting a fluid under pressure to the interior of said expandable member, whereby said expandable member will be expanded and exert a 15 pressure against the clothes to squeeze water therefrom when raised out of the water in the tub by an elevating of said clothes agitating member.

13. In a clothes washing machine of the character described, the combination of a stationary 20 tub adapted to contain a washing fluid, a hollow stationary pedestal forming a part of said tub and extending centrally above the top thereof, elevating means arranged within said hollow stationary pedestal and extendible from the top 25 of said hollow stationary pedestal, a saddle-like supporting member engaging the extendible end of said elevating means and extending downwardly over the outside of said hollow stationary pedestal and into the tub, a dished clothes supporting element carried by said saddle-like supporting member and having a plurality of radially disposed slots in the bottom thereof, a plurality of agitator vanes associated with said dished clothes supporting member adapted to project 30 through the radially disposed slots thereof, and means at the bottom of said tub arranged so as to project said agitator vanes upwardly through the radially disposed slots of said clothes carrying member when the latter is lowered into the 40 tub and to permit said agitator vanes to move downwardly with respect to said clothes carrying member and into an inoperative position when said clothes carrying member is elevated for a removal of the clothes from the tub.

14. In a clothes washing machine of the character described, the combination of a stationary tub adapted to contain a washing fluid, a hollow stationary pedestal disposed centrally within said tub and extending above the top thereof, an elevating means movable within said hollow pedestal and extendible from the top thereof, a saddle-like clothes supporting and agitating element encasing said hollow stationary pedestal and connected at its upper end to the elevating means within said pedestal and adapted to move in unison therewith, said saddle-like element having a dished clothes supporting flange with radial slots in the bottom thereof, agitator vanes cooperating with said clothes supporting and agitating element movable through the radial slots thereof as said clothes supporting and agitating element is raised and lowered within the tub by said elevating means, and means at the bottom of said tub arranged to project said agitator vanes upwardly through the slots in the clothes supporting flange of said saddle-like element and into an operative position when said element is lowered into its clothes washing position and 70 permit said vanes to move into an inoperative position when the clothes supporting and agitating element is raised within said tub by said elevating means.
